UNITED STATES PATENT OFFICE.

HENRY H. NORRINGTON, OF WEST BAY CITY, MICHIGAN.

SCORE-INDICATOR.

SPECIFICATION forming part of Letters Patent No. 710,993, dated October 14, 1902.

Application filed November 29, 1901. Serial No. 34,050. (No model.)

To all whom it may concern:

Be it known that I, HENRY H. NORRINGTON, a citizen of the United States, residing at West Bay City, county of Bay, State of Michigan, have invented a certain new and useful Improvement in Card-Cases and Score-Indicators; and I declare the following to be a full, clear, and exact description of the invention, such as will enable others skilled in the art to which it appertains to make and use the same, reference being had to the accompanying drawings, which form a part of this specification.

My invention has reference to a combination reversible card-case and score-indicator; and it consists of the construction, combination, and arrangement of parts hereinafter described and claimed, and illustrated in the accompanying drawings, in which—

Figure 1 is a view in perspective, illustrating features of my invention. Fig. 2 is a plan view showing the cover in one of its positions. Fig. 3 is a plan view showing the cover in the reverse position from that shown in Fig. 2 with the indicator or counter turned uppermost. Fig. 4 is a view similar to that shown in Fig. 2, the surface of the cover uppermost being shown as a cribbage-board. Fig. 5 is a cross-section showing the cover in raised position.

The object of my invention, more particularly, is to provide a box embodying a card-case in which a pack of playing-cards may be kept when not in use, the box being provided with a reversible cover having in combination therewith one or more score-indicators or means for recording the game or various kinds of games, the card-case and score-indicator forming a single combined structure.

The score-indicator being in combination with the card-case, always forms an inseparable portion thereof, so that in the single structure I provide a receptacle for the cards, together with means for keeping the score for recording the games. Heretofore it has been necessary to have independent methods for counting or scoring the games by separate devices unattached to the card case or receptacle. My invention, however, is intended to provide a compact method and means for a card-receptacle and score-indicator. Obvi-

ously such a structure is economical and convenient and of superior efficiency.

I carry out my invention as follows:

In the drawings, *a* denotes a box having 55 side walls *b* and end walls *c*, the end walls being provided with upwardly - projecting flanges *d* and *e* and horizontal flat portions *f* and *g*. On the rear ends of said flanges are metal bearings *h h*. The reversible cover is 60 shown at *i*, provided with arms *j k*, journaled in said bearings. The ends of the cover seat upon the horizontal portions *f* and *g* of the end walls, leaving a chamber *l* therebeneath for holding a pack of cards. Upon one side 65 of the reversible cover I have located and arranged counting or score-indicating devices consisting, essentially, of duplicate dials *m m*, upon which to score or count the points made, and additional dials *n n*, upon which to score 70 or count the number of games. The dials *m m* may be arranged and constructed to score units, while the dials *n n* may be constructed and arranged to score tens, the latter dials not being limited to scoring the number of 75 games. It will be understood that one of the dials *m* and one of the dials *n* are employed for each side in the game. The dials *m* are provided with numerals "1," "2," "3," "4," "5," "6," "7," "8," and "9" and preferably, 80 also, with ciphers located intermediate of said numerals. The dials *m m* are provided with fingers *p p* and the dials *n n* are provided with rotatable index-fingers *q q*. The provision of the ciphers interposed between the numerals 85 "1," "2," "3," "4," "5," "6," "7," "8," and "9" on the dials *m m* enable the player to count not only tens, but up to one hundred points, since after the index-finger has been moved about its corresponding dial to count 90 ten points it may be moved subsequently to the ciphers in succession to indicate tens, twenties, &c., up to one hundred.

The dials are intended to be closed inward when the case is not in use, the cover being 95 reversed when the device is in use. The opposite face of the cover may be left plain or ornamented, as shown in Fig. 2 or as in Fig. 4. The face of the cover opposite the dials may be constructed for chess, cribbage, or other 100 games, the cover being formed for a cribbage-board as shown in Fig. 2.

Any suitable devices, as hooks *r* and eyes *s*, may be employed to hold the cover in closed position. I do not limit myself solely to providing the cover with dials, as my invention 5 contemplates the provision of the reversible cover with means for keeping a record of counts for games in any desired manner on one or on both sides of the cover.

What I claim as my invention is—

- 10 A card-case and score-indicator embodying in combination a box formed with end and side walls, the end walls being constructed with inner horizontal flat portions and with vertical flanges projecting above the flat portions and above the side walls, a reversible cover, arms having a pivotal connection with the cover at the longitudinal center thereof, and at their outer ends having a pivotal connection with the rear ends of the said flanges,

20 said cover seating with either face of the cover uppermost upon the inner flat portions of the end walls and upon the upper edges of the side walls between said flanges, forming a receptacle beneath the cover to contain the cards and housing the arms between the ends 25 of the cover and said vertical flanges, said cover provided on one side thereof with a dial to indicate the points of the game and with a dial to indicate the number of games, the other side of said cover provided with a 30 game-board.

In testimony whereof I sign this specification in the presence of two witnesses.

HENRY H. NORRINGTON.
